UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING AND LOADING MACHINE.

1,290,021.

Specification of Letters Patent. Patented Dec. 31, 1918.

Original application filed August 7, 1913, Serial No. 783,564. Divided in part and this application filed August 7, 1913. Serial No. 783,565.

To all whom it may concern:

Be it known that I, NILS D. LEVIN, a citizen of the United States, residing at Columbus, in the county of Franklin and State of Ohio, have invented certain new and useful Improvements in Mining and Loading Machines, of which the following is a specification, reference being had therein to the accompanying drawing.

10 The invention relates to mining and loading machines which are provided with means for undermining coal in its natural bed, means for breaking it down out of the said bed, and means for loading it onto cars by means of which it is removed from the mine.

I am well aware that machines for this class of work have been heretofore proposed, but according to earlier proposals, machines constructed to carry on the three operations

20 above enumerated have been adapted only to attack a coal face substantially perpendicularly. According to my invention the machine can be moved in a curved path substantially parallelly to the curved forward

25 face of a mine room and can undercut and break down a long curved strip of coal and convey the broken coal to points relatively remote from the face. One object of my invention therefore is to provide a machine

30 having its parts arranged as above described to move in a curved path. Another object of the invention is to provide in a machine adapted to move substantially parallelly to a coal face whether on curved

35 lines or straight lines, the combination of an undercutting means, and a breaking down device adapted to attack the coal wall located behind the undercutting means and in a plane transverse and substantially perpendicular to the main face of the coal.

40 Still further objects of the invention are to provide certain improved features of construction which will be fully apparent from the following specification. In the accompanying drawings I have shown constructions which are intended merely to be illustrative of the invention and various modifications and changes can be made within the scope of the claims appended to the specification.

45 Of the drawings—

Figure 1 is a diagrammatic plan view of the machine in operative position in a mine.

Fig. 2 is a diagrammatic side view of the machine.

Fig. 3 is a plan view showing the machine in detail.

Fig. 4 is a side view showing the machine in detail.

Fig. 5 is a diagrammatic view, partly in section, showing the breaking down device.

Fig. 6 is a sectional view taken along the lines 6—6 of Fig. 3.

Fig. 7 is a sectional view taken along the line 7—7 of Fig. 3.

Fig. 8 is a detail view showing part of the breaking down device.

Fig. 9 is another detail view showing a part of the breaking down device.

Fig. 10 is a longitudinal sectional view taken along the gathering conveyer.

Fig. 11 is a diagrammatic plan view illustrating the manner of moving the machine bodily forward in a mine.

The machine is provided with an undercutting mechanism which is similar to the mechanisms which have been used for mining machines for longwall work and for mining machines for undercutting transversely across the face of a mine room. It consists of a cutter chain 1 which is driven by a sprocket wheel 2 and which travels in guide-ways on a cutter-head 3 secured to the main frame casting 4. The sprocket wheel 2 is carried by a vertical head shaft 5 which is journaled in suitable bearings 6 and 7. Near the upper end of the shaft 5 is a master gear 8 which meshes with the pinion 9 on the armature shaft of the motor 10. Conveniently located on the main frame is a bracket 11 in which is journaled a feed shaft 12 carrying a feed drum 13. 14 is a rope adapted to be wound at one end upon the feed drum 13 and to be connected at the other end to a suitable jack 15 which is so located that the strain on the rope will draw the cutter-head into the coal to be cut.

Keyed to the upper end of the feed shaft 12 is a worm wheel 16 which is driven by a worm 17 secured to the shaft 18. The shaft 18 is journaled in suitable bearings on the main frame and carries a ratchet wheel 19 which can be engaged by a pawl 20. The pawl is mounted on an arm 21 which is mounted to oscillate about the shaft 18 as a center. By means of the rod 22 the arm 21 is connected to an eccentric 23 on the shaft 5. Journaled on the shaft 18 on opposite sides of the ratchet wheel 19 are arms 24, the

outer ends of which are connected together by a trunnioned nut. Threaded in this nut is a screw 26 which is connected to the main frame. Mounted upon the arms 24 is a shield 27 adapted to be carried by the arms into the path of the pawl 20 to hold it out of engagement with the teeth of the ratchet wheel. A hand wheel 28 is secured to the screw 26 and by means of this hand wheel the screw can be adjusted to move the shield with respect to the pawl. As the pawl is oscillated by means of the arms 21 it will be held out of engagement with the ratchet wheel 19 during more or less of its stroke 10 according to the position of the shield 27. In this way the operator by means of the hand wheel 28 can control the rotation of the feed drum 13.

The main frame casting 4 is extended over 20 the floor of the mine to form a flat plate or pan 29. This plate is positioned in the plane of the bottom of the kerf cut by the undercutting mechanism and is adapted to be pushed under any loose coal or slack and to 25 receive any coal that may be loosened and broken down upon it. Formed at the extreme inward and rearward corner of the plate 29 is an upward extending flange 30.

Supported upon the flange 30 is a slide-way 31 in which is mounted for longitudinal adjustment a base casting 32. Upon this base casting there is universally pivoted a pick mechanism which may be of any well known type. The preferred construction

35 which is shown will be described in detail, but it will be understood that other forms of pick mechanism may be used without departing from my invention. The pick mechanism shown consists of a main cylinder casting 33 in which there is slidably mounted a cylinder 34 carrying at its forward end a rod 35. Attached to the forward end of the rod 35 is a hammer 36 adapted to strike the end of a pick tool 37 to drive it against the coal. 40 Within the cylinder 34 are two springs 38 and 39, each bearing at one end on one end of the cylinder and at the other end against one side of the piston 40. Connected to the piston 40 is a piston rod 41 which is connected by

50 means of the connecting rod 42 to a crank pin 43 on the worm wheel 44. The worm wheel meshes with a worm 45 on the shaft of a motor 46 mounted on the frame casting 33. Formed on the main cylinder casting 33 are 55 trunnions 47 which are journaled in suitable bearings in upstanding arms 48 on a pivot casting 49. The casting 49 is provided with a bearing stud 50 which is seated in a suitable aperture in the base casting 32. The casting 32 is provided with a depending lug 51 having a threaded aperture adapted to receive and to be engaged by a rotary threaded rod 52 which can be turned by means of the crank 53. The operator by turning the crank

65 53 can move the casting 32 in the slide-way

31 and thus adjust the whole pick mechanism longitudinally.

The pick tool 37 is freely slideable in a guide-way, one part of which is formed integrally with the casting 33 and is indicated in the drawings by 54. The other part of the guide-way consists of the plate 56 which is hinged to the part 54 by means of the lugs 55, 55 and can be secured in place by means of the bolt 57 and the nut 58. By means of this construction the pick tool can be readily secured in place and can be readily loosened for removal.

Positioned within the forward end of the cylinder casting 33 is a solenoid 33^a surrounding the adjacent ends of the hammer 36 and the pick tool 37. When this solenoid is energized it sets up magnetic currents through the hammer and the pick tool aid serves to hold them in contact, the tool reciprocating 85 with the hammer.

Positioned on the main cylinder casting 33 is a handle 59 by means of which the pick mechanism can be swung about the transverse axis of the trunnions 47 and about the vertical axis of the bearing stud 50. By means of this handle the operator has complete control of the pick mechanism to effect vertical and transverse adjustment, and by means of the crank 53 can effect longitudinal 95 adjustment.

The machine here selected for illustrating one form embodying my invention is provided with a pivot device adapted to be placed on the center line of the mine room or entry being worked. This pivot device comprises a base plate 60 having a plurality of upward and inward extending arms 61 which are joined to form a bearing 62. This bearing 62 carries a vertical column 63, the upper part of which is screw-threaded for engagement with a threaded hand-wheel 64. Above the hand-wheel is a sleeve 65 at the upper end of which is a cap 66 which is adapted to engage the mine roof. By turning the hand-wheel the cap can be forced against the roof and the whole pivot device securely anchored in place.

Pivottally mounted on the column 63 and supported by the bearing 62 is the head casting 67 of the conveyer 68. The frame of the conveyer extends from the head casting 67 to the base plate 29. This conveyer frame serves as a radial strut to guide the operative parts of the machine in a circular path about the pivot devices as a center. The conveyer 68 comprises an endless chain which travels in suitable guideways and carries horizontally extending flights or scrapers which push the material along a suitable trough. 125 69 is a head sprocket for the chain and this is journaled upon a sleeve 70 formed on the head casting 67.

The head sprocket 69 has connected to it a drive sprocket wheel 71 which is engaged by 130

a chain 72, the chain also passing over a sprocket wheel 73 on the shaft 5.

The chain for the conveyer 68 is indicated in the drawings by 74 and to this chain are 5 attached flights 75 adapted to engage material on the plate 29 and move it into and along the trough 76 which extends along the conveyer frame from the plate 29 to a point of discharge near the head of the conveyer. 10 The conveyer frame consists of suitable structural steel shapes 77 which are arranged to serve as guides for the conveyer chain 74. These guides are bolted at one end to the head casting 67 and at the other end to a 15 casting 79 secured to the plate 29 by means of bolts 80. The foot sprocket for the chain is indicated by 81 and this is mounted upon a pin 82 secured in a casting 83. The casting 83 is connected to the plate 29 by means of 20 bolts 84 which extend through slots in the casting. By means of a screw 85 the casting 83 together with the foot sprocket can be adjusted with respect to the main part of the conveyer frame to regulate the tension in the 25 chain.

The machine is also provided with a second conveyer 87 which is of the same type as the main conveyer 87. It is mounted on a truck 88 having wheels 89 resting on the 30 rails of the mine track 90. The inward end of the trough of the conveyer 87 is formed with a receiving hopper 91 adapted to rest on the plate 60 between the arms 61 to receive the material discharged from the gathering conveyer 68. An endless chain with scrapers 92 carries the material through the trough 93 and discharges it into a car 94 on the track 90. This conveyer 87 is driven by the sprocket wheel 95, the chain 96, the 40 sprocket wheel 97, the vertical shaft 98, the worm gearing at 99 and the motor 101. This motor is mounted on the truck 88.

Referring to the operation of the machine, the pivot device is first secured in position 45 at the center of a room, as shown in Figs. 1 and 3. The swinging part is initially positioned at the extreme right hand side of the room and the feed rope is connected to a jack 15 positioned at the extreme left hand side. Posts or jacks 102 are placed along the curved face of the room for holding the rope in position intermediate its ends. A car 94 having been placed in position the 50 motors are started and the machine advances 55 under the action of the feed mechanism.

As the machine advances under the influence of the feed mechanism the undercutting mechanism cuts the kerf at the bottom of the room into the curved coal face, this 60 kerf gradually increasing in depth to the center of the room and decreasing in depth after the center of the room is passed. Obviously the stress on the machine will be less during the initial and the latter parts of the 65 cut and the feed mechanism can therefore

be advantageously varied to cause the machine to move faster at the ends of the cut than at the center. In this way the rate of cutting and removing the coal can be kept substantially constant.

As the machine feeds into the coal the pick mechanism is brought to bear against the rear, traverse wall formed behind the undercutting mechanism, at first near the bottom and afterward higher up, breaking out fragments of coal which fall upon the plate 29 and are caught by the conveyer flights 75 and moved up the conveyer trough. The coal discharged from the first conveyer is caught by the second conveyer and finally 80 deposited in the car. It will be seen that the operator has full control of the pick mechanism to move it vertically or laterally with respect to the direction of movement or to move it longitudinally. In this way it is 85 possible to attack the whole surface of the exposed rear wall which extends transversely to the face along which the machine advances.

In Fig. 11 I have indicated diagrammatically the method of moving the machine bodily from one position of use to another. At the end of a cut the swinging part of the machine is moved backward to the right hand rib of the room and then the feed rope 95 is carried forward over a snatch block on a jack 103 and is carried back and secured to the main pivot device which is then loosened. When the feed rope is wound it serves to draw the whole machine bodily forward 100 into position indicated by dotted lines in Fig. 11. When this position is reached the pivot device is then secured in place and another cut is started.

When the cutting mechanism and its carrying frame are arranged, as in the mechanism herein shown, to swing around a vertical axis, the free face of the rear wall newly formed by the breaking mechanism, will be in planes approximately longitudinal of the 110 carrying frame although not exactly longitudinal in relation to the lines of the mine room or chamber. When the front face is more nearly flat or straight, transversely, the plane of the newly broken face of the 115 rear wall will be approximately longitudinal, both in respect to the room and in respect to the machine.

I do not herein claim any of the specific subjects matter presented in the claims in 120 my copending application 783564, filed August 7, 1913, or presented in the claims in my application 19746, filed April 7, 1915, both of said applications showing and describing machines designed to move approximately 125 rectilineally along a coal bed, having a straight or comparatively flat front face, I preferring to herein claim subjects matter which can be embodied either in a horizontally swinging structure, such as that herein 130

illustrated, or in mechanisms moving on straight lines, such as are therein illustrated.

In my aforesaid application 783564 there are combined an undercutting mechanism, 5 breaking-down devices and a conveyer. The breaking-down means in that apparatus are devices which have a wedging action and are made active by the practically constant forward draft force exerted by the feeding 10 mechanism. In the present apparatus the breaking down of the coal is effected by a blow-imparting pick mechanism having peculiar advantages incident to it when constructed and related to the other parts as is 15 herein described.

The present mechanism is of a class readily distinguishable from "heading" or "breast" machines. The latter are each constructed and operated in such way that the 20 cutters and the cutter carriers, when at work, advance directly inward on longitudinal lines at right angles to the vertical planes of the normal front coal face, for example the face at the inner end of a 25 "room", the latter being bounded along its sides by fixed vertical coal walls. Such breast or heading machines have been provided with reciprocating coal breaking picks but the latter were arranged to strike blows 30 on longitudinal lines, that is, lines parallel to the lines of the direct inward longitudinal thrust of the cutters, and conveyers situated centrally between the sides have been used with these heading machines.

35. Machines of the other class (which includes the present mechanism) are designed to have the principal movement of the cutter carrier, while at work, occur, not on lines intersecting, but on lines parallel to the normal front coal face, and to have a continuous traveling movement across the entire face.

40. And with apparatus of this class, also, it has been proposed to combine conveyers 45 for automatically taking the coal away from the face on lines at right angles thereto.

Some of the machines of this sort have 50 been designed to get the coal out in blocks, smaller or larger, this to be done by forming multiple kerfs (horizontal or vertical or both) and kerfs formed by saw-like cutters rotating in planes inside of, parallel to and at a distance from the planes of the normal front face, that is, so positioned as 55 to follow the planes of the next succeeding front face.

In other cases a cut is formed of the shape 60 of a large loop, which severs a block of the coal at the top and at the bottom, and at vertical lines (inwardly remote from the front face) connecting the top kerf section and the bottom kerf section.

In still other cases it has been proposed 65 to cut a horizontal kerf in relatively high horizontal planes along the front face and

then put into operation a machine having an undercutter and a rocking wedge mechanism, the latter to travel in the upper kerf formed during the aforesaid preliminary operation.

If a mechanism of any of the classes just referred to be used, it will form a relatively shallow horizontal kerf, which extends on longitudinal lines inward from the front face and on transverse lines along said face, 70 and also a chamber which widens vertically from the horizontal kerf, and is gradually elongated transversely, and has at its forward end a longitudinally disposed transversely advancing vertical wall positioned 80 approximately in longitudinal vertical planes intersecting the planes of the normal front face of the coal; this being in contradistinction from the chamber formed and the manner of forming it, incident to the 85 use of the "heading" or "breast" machine. The present mechanism differs materially from all of the earlier machines which move bodily continuously on transverse lines, that is, on lines parallel to the front face, in that 90 I provide a blow-striking, coal-breaking tool which is so arranged as to produce the transversely advancing coal face that intersects the vertical planes of the normal front face, the tool being adapted to impart the 95 blows at option at any of the points distributed vertically and longitudinally over this transversely advancing face.

Such mechanism enables me to dispense with the numerous cutting elements and 100 the complicated cutter carriers which have been necessary to carry and to operate the cutters in the other mechanisms above referred to. The kerf extends from six to eight feet under the coal and provides clearance for the vertical movement of the mass when dislodged. The mass being without support at the front face, it is comparatively easily dislodged at the top and at the inner vertical planes by the blows of the 105 pick. These can be delivered at points immediately adjacent to the kerf or at points near to the top of the coal mass. Most of the coal formations are such that when a single clearance kerf is cut the blows of the 110 tool are sufficient to separate the material at the inner vertical lines of the kerf from the solid native mass beyond them. I do not limit myself to a single horizontal kerf but have found this sufficient where the coal 115 is not one of the tougher or more tenacious sorts. A breaking down device of this sort is of advantage when it is desired to employ a conveyer such as is illustrated. The receiving end of the conveyer can be placed 120 close to the transversely advancing break wall and in the vertical lines of the dropping masses as the pick mechanism can be arranged to operate across the vertical longitudinal planes of the conveyer and be ad- 125 130

justed vertically or horizontally as desired, without either of these parts of the mechanism interfering with the other. The coal dropping from the pick point falls directly 5 to the conveyer.

This rear wall or free face is in a vertical plane which is at an angle or is inclined to the normal front face, and it is approximately parallel to the vertical plane of the 0 lines along which the undercutters act as they advance. The blows of the pick are delivered on lines approximately perpendicular or at right angles to the said vertical plane at the forward end of the kerf. 5 The mechanism in this respect differs from those in which undercutters have been used which are thrust directly forward into the coal, and above which drills have been placed whose blows are directed against the 0 front normal face of the coal.

What I claim is:

1. In a mining mechanism adapted to travel continuously along the normal front face of a coal bed and to form a relatively 5 shallow horizontal kerf which extends on longitudinal lines inward from the front face and on transverse lines along said face and to also form a chamber which widens vertically from the horizontal kerf and is 0 gradually elongated transversely along the face and has at its forward end a transversely advancing vertical wall in planes intersecting the walls of the normal front face of the coal, the combination of a frame 5 movable continuously along said normal front face, an inward projecting horizontal kerf cutter carried by the frame, a tool holder carried by said frame, a blow-striking coal-breaking pick mounted on said 0 holder and adjustable as set forth to impart blows to the coal at optionally selected points distributed vertically and longitudinally over the said transversely advancing longitudinal face.

2. In a mining apparatus of the class described, the combination of the frame adapted to be moved while in operation along the normal front face of a native coal bed, means engaging said frame to hold it to 0 predetermined lines of travel transversely along said face, means for fastening the said frame holder at successive points along longitudinal lines intersecting said face, for successive operations, a horizontal kerf cutter carried by said frame, and a blow-striking coal-breaking pick movable bodily on lines parallel to said lines of advance of the kerf cutter and arranged to break down the undercut coal and form a transversely 5 advancing face positioned in vertical planes intersecting the planes of the front coal face and to optionally apply blows in different directions at points distributed over the said longitudinal transversely advancing face.

3. In a mining apparatus of the class described, the combination of the frame adapted to be moved along and close to the front face of a native coal bed, means engaging said frame to hold it to predetermined 70 transverse lines of travel, devices for fastening said holding means in place at successive points along longitudinal lines intersecting said face, a horizontal kerf cutter carried by said frame, a tool holder 75 movable bodily on lines parallel to the lines of advance of the kerf cutter and held to said lines by said fastening devices, and a blow-striking coal-breaking pick mounted on said holder and arranged to break down 80 the coal behind the kerf cutter and form a chamber with a transversely advancing wall extending vertically from the horizontal kerf, said pick being adapted to impart blows in optionally varied directions at 85 points distributed over the said transversely advancing face.

4. In a coal mining apparatus adapted to be moved bodily, while operating, on lines parallel and close to the normal front face 90 of a native bed of coal, the combination of an inward projecting horizontal kerf cutter, a frame carrying said cutter and having an element extending into and movable in the kerf, a support on said frame element positioned in vertical lines inside of the planes of the said front coal face, a horizontally swinging tool carrier on said support, and a vertically adjustable blow-imparting coal-breaking pick mounted on 95 said carrier and positioned bodily inside of the vertical planes of the front coal face, said pick being adapted to impart blows to the coal above the kerf and directed on lines approximately parallel to the lines of advance of the kerf cutter. 100

5. In a mining apparatus of the class described, the combination of the frame adapted to be positioned close, and to be moved 110 parallel, to the normal front face of a native coal bed, means to hold the frame to predetermined lines while advancing transversely along the face, an inward projecting horizontal kerf cutter carried by said frame, fastening devices to secure the frame 115 holder at successive points along longitudinal lines intersecting the said face, a tool holder mounted to travel bodily simultaneously with the coal cutter along said front face, a blow-striking, coal-breaking pick mounted on the said tool holder and arranged to break down the coal behind said cutter and form a chamber with a transversely advancing wall, said pick being arranged to impart blows to said transversely advancing wall at points distributed vertically and horizontally over its face, and power actuated feeding means arranged to exert draft on the pick at points near the 120 planes of the front face of the coal. 125

6. In a coal mining apparatus adapted to be moved bodily, while operating, on lines close and parallel to the normal front face of a native coal bed, the combination of means for cutting a horizontal kerf in the coal, a conveyer having its forward lower end positioned relatively behind the kerf cutter to receive broken down coal, a power-actuated blow-striking coal-breaking 10 pick-like tool positioned to extend, when in operation, across the vertical longitudinal planes of the conveyer and to break down the coal thereupon, and form a gradually elongating transversely positioned chamber 15 behind the kerf cutter and having a forward advancing wall with a vertical face in planes intersecting the vertical planes of the normal front face of the coal, said pick being universally adjustable and adapted to 20 strike blows at points distributed over the face of the said transversely advancing wall, means supporting the kerf cutter and the pick, means connecting their supports rigidly together, and means for advancing 25 them together bodily along the front face of the coal.
7. In a mining mechanism adapted to travel continuously along the normal front face of a coal bed and to form a relatively shallow horizontal kerf and to remove the coal positioned in the vertical lines of the kerf by a blow-striking picking action without the forming of supplemental kerfs either horizontal or vertical, the combination of a frame adapted to be moved continuously along said normal front face, a cutter carried by the frame for forming a single relatively shallow horizontal kerf which is continuously lengthened transversely while the machine is in operation, and a blow-striking coal-breaking pick 40 movable bodily on lines parallel to the lines of advance of the kerf cutter and arranged to break down the coal in the vertical lines of said kerf and separate it from the overlying material and also separate it from its native bed on the innermost vertical lines of the kerf, said pick being adapted to form a transversely advancing face in planes intersecting the planes of the front face by 45 imparting blows in optionally varied directions at points distributed over the said transversely advancing face.
8. In a mining mechanism adapted to travel continuously along the front face of a coal bed and form a single relatively shallow horizontal kerf and to dislodge the coal remaining in the vertical lines of said kerf and form parallel to the face a gradually elongating transverse chamber by 55 intermitting coal dislodging blows which separate the undercut coal by cleavage from the overlying material and by cleavage sep-

arate it from the solid mass beyond it, the combination of a frame, means for moving it along said normal front face, a cutting mechanism carried by the frame which forms a single relatively shallow horizontal kerf, a blow-striking coal-breaking pick arranged to impart blows to the coal and form 65 behind the kerf cutter a chamber with a gradually advancing forward wall and to break the coal above the kerf from the solid material above it and also break it from the solid native coal behind it, said coal 70 breaking pick being connected to the frame and to the kerf cutter, to be moved there-with along the face of the coal.

9. The combination of a main frame movable laterally along the coal face, a horizontally projecting cutter to undercut the coal, a plate arranged to move in the kerf beneath the undercut coal, a conveyer extending in operation from points outside the coal face to points near the innermost 85 line of the kerf and arranged to follow the lines of travel of the cutters and to have said plate deliver coal thereto, the motor and power mechanism on the main frame in front of the conveyer, and means for breaking 90 the coal down adapted to attack the coal above the conveyer and on vertical planes at an angle to the front face of the coal.

10. The combination of the main frame movable laterally along the coal face, the cutting apparatus projecting therefrom to undercut the coal, means on the frame outside the bounding lines of the coal face for moving the frame and cutting apparatus laterally along the face of the coal, and a 95 coal breaking pick carried by the frame and arranged to impart blows on lines approximately at right angles to the vertical plane of the forward end of the kerf formed by the undercutters.

11. The combination of the main frame movable laterally along the coal face, the cutters projecting therefrom to undercut the coal, means on the frame outside the bounding lines of the coal face for moving the 110 frame and the undercutters along the face of the coal, said frame extending into the kerf formed by the undercutters, and a coal breaking pick carried by the frame and adapted to form a free face on the coal inside of and at an angle to its normal front face and said pick being arranged to impart 115 blows to a face such as last aforesaid while bodily advancing with the cutting apparatus.

In testimony whereof, I affix my signature in presence of two witnesses.

NILS D. LEVIN.
